UNITED STATES PATENT OFFICE.

JOHN EVANS, OF PHILADELPHIA, PENNSYLVANIA.

HOT-AIR FURNACE.

SPECIFICATION forming part of Letters Patent No. 610,037, dated August 30, 1898.

Application filed January 17, 1898, Serial No. 666,873. (No model.)

To all whom it may concern:

Be it known that I, JOHN EVANS, a citizen of the United States, residing at the city of Philadelphia, in the county of Philadelphia and State of Pennsylvania, have invented certain new and useful Improvements in Hot-Air Furnaces, of which the following is a specification.

My invention has relation to a hot-air furnace, and in such connection it relates particularly to the construction and arrangement of the parts comprising such a furnace.

The principal objects of my invention are, first, to reduce the cost of such a furnace by simplifying the construction and arrangement of the parts thereof as well as by reducing the number of such parts; second, to increase the efficiency of the furnace by utilizing in an economical manner all the heat products and by increasing the amount of heat arising therefrom by causing a more complete combustion of the gases and other products; third, to prevent during the operation of the furnace the escape of gas, smoke, or other products of combustion into the hot-air-supply conduits or tubes; fourth, to permit of the entrance of the cold air at a point which will prevent the entrance therewith of dust, and, fifth, to utilize the products of combustion so that the air in the ash-pit may be warmed and to present this warmed air below and above the grate of the furnace.

My invention, stated in general terms, consists of a hot-air furnace constructed and arranged in a manner substantially as herein-after described and claimed.

The nature and scope of my invention will be more fully understood from the following description, taken in connection with the accompanying drawings, forming part hereof, and in which—

Figure 1 is a vertical sectional view of a hot-air furnace embodying main features of my invention, said section being taken on the line 1 1 of Fig. 3. Fig. 2 is a transverse sectional view on the line 2 2 of Fig. 1. Fig. 3 is a similar sectional view on the line 3 3 of Fig. 1. Fig. 4 is a vertical sectional view of the lower portion of the furnace, said section being taken on the line 4 4 of Fig. 5; and Fig. 5 is a transverse sectional view on the line 5 5 of Fig. 4.

Referring to the drawings, A represents the exterior casing of the furnace supported upon a raised bed-plate A' and supporting at its upper edge a ring A², upon which the dome or air-drum A³ is supported, from which dome a series of hot-air pipes A⁸ radiate and lead to the various registers in the house. Within the casing A, and supported by the bed-plate A', substantially as hereinafter described, is arranged a series of box-shaped castings a, one side a' of each of which is curved and rests adjacent to the fire-pot B and combustion-chamber D of the furnace, whereas the opposite side is open and provided with flanges or wings a², which when the castings are assembled together overlap, as shown in Fig. 3, and form spaces b between the boxes, which spaces, as hereinafter described, form flues for the passage of the products of combustion. The lower ends of these castings a converge or taper to a flat portion a³, which rest in an annular groove a⁴, formed in the bed-plate A', as shown in Fig. 1, and the flat portions a³ of the castings form when the parts are assembled a circular wall surrounding the base of the ash-pit E, as shown in Figs. 1 and 5. The inner side of the fire-pot B is provided with a ledge d, serving as a support for the shell d' of the combustion-chamber D, and the outer side of these castings a is also provided with a ledge e, serving as a support for the cylindrical shell e', which serves to close the open sides of the castings, as shown in Figs. 1 and 3, and to form therewith hot-air conduits a⁵. The casting f of the ash-pit E is supported at its front end by an external casing A⁴ and near its rear end by a girder f', resting on the bed-plate A' or in any suitable manner. The casing f of the ash-pit rests at its upper edge against the inner surface of the castings a at the point where said castings begin to taper, and this upper edge is provided with a ledge g, serving as a support for the ring or shell B' of the fire-pot B and also for the fire-brick g', forming the lining of the fire-pot B, as shown in Fig. 1. These bricks g' rest directly against the shell B' of the fire-pot B, but are provided with grooves or conduits g², having an upper outlet g³ into the base of the combustion-chamber D and lower inlets g⁴ communicating with the interior of the ash-pit.

below the grate F, as shown in Figs. 1 and 3. The purpose of this arrangement will be described hereinafter. The shell d' of the combustion-chamber D is provided with a ledge 5 m, adapted to support a funnel-shaped piece m', which serves to guide the products of combustion directly upward.

Above the castings a and preferably secured thereto by bolts is located a cap G, shaped in cross-section as shown in Fig. 2, and it consists of a number of box-shaped arms or projections h, the interior of which communicate directly with a central chamber h', located directly above and surrounding the funnel-shaped piece m' of the combustion-chamber D. The interior of the arms h also communicate through openings b' with the flues b. The arms h are separated from each other by similarly-shaped spaces h², which are directly in communication with the top of the air-chambers a⁵, formed by the castings a, and also with the interior of the air drum or dome A³, as shown in Fig. 1. The lower ends of the flues b are open, as at b², and communicate directly with the space f² below the ash-pit E, whereas the lower ends of the air-chambers a⁵ are open, as at a⁶, and communicate with the space a⁷, formed between the casing A and the exterior face of 30 the castings. The bed-plate A' is provided with a number of openings a⁸, as shown in Figs. 1 and 5, to permit communication between the space a⁷ and a space a⁹ below the bed-plate A'.

35 The off-take pipe H for the smoke and other products of combustion is continued vertically down the side of the furnace and is provided with two branch pipes H' and H², of which the pipe H' leads directly to the combustion-chamber D, whereas the other pipe H² leads to the space f² below the ash-pit E, as illustrated in Fig. 4. The off-take pipe H extends within an extension A⁵ of the casing A. This extension A⁵ serves as a jacket for 40 the pipe H and also as a duct for the entrance of cold air, which air enters at the top of the jacket near the top of the furnace and passes down the pipe H to an opening A⁶, through which it passes into the space a⁹ below the bed-plate A'.

An important feature of the present invention resides in the manner of securing the castings a together to form the air-chambers a⁵ and flues b, so that the products of combustion in the flues or other parts of the furnace cannot enter the air-chambers. To accomplish this, the castings a, as hereinbefore described, are provided at their sides with the flanges or wings a³ and at their tops with 55 the flanges a¹⁰ and a¹¹. These flanges overlap, and between the overlapped flanges a sheet or layer a¹², of asbestos paper or similar fireproof material, is placed prior to the bolting of the flanges together. With this construction expansion and contraction of the 60 castings due to changes in temperature within the furnace may take place without disturb-

ing the tightness of the joint thus formed, the wings or flanges sliding over each other without separating.

70 In securing the cap G to the castings a a similar construction is employed. In this instance the flange G' of the cap overlaps the flange a¹⁰ or a¹¹ of the castings, and between these flanges G' and a¹⁰ or a¹¹ a layer of asbestos paper a¹² is inserted before the flanges are bolted or otherwise secured together.

In operation fire is started in the fire-pot B, and the smoke and products of combustion enter the combustion-chamber D. From 80 this chamber a portion of the products pass through the pipe H' to the off-take pipe H, near the upper end of the jacket A⁵. The remainder of the products of combustion ascend to the chamber h' of the cap G and are 85 deflected through the interior of the arms h to the flues b, from which it passes into the space f² below the ash-pit E, heating said ash-pit, and then passing out through the branch pipe H² into the off-take pipe H. The 90 air which is admitted to the ash-pit E through its door E' is heated before it enters below the grate F by the passage of products of combustion around the ash-pit, and a portion of this heated air in the ash-pit passes through 95 the openings or inlets g⁴ and the grooves g² and the outlets g³ into the combustion-chamber D, serving thereby to materially assist in the combustion of gases and other products in said chamber D. The passage of the products of combustion through the flues b serves to highly heat the castings a, which from their close proximity to the fire-pot and combustion-chamber are also highly heated by the combustion of products in said fire-pot 100 and combustion-chamber. The cold air enters at the top of the jacket A⁵ and passes down the heated off-take pipe H into the space a⁹ below the bed-plate A', and from thence through the openings a⁸ into the space 110 a⁷ between the castings and casing A, and thence into the air-boxes a⁵, from which it is delivered to the spaces h² of the cap G and to the dome or air-drum A³ and escapes into the pipes A⁸, leading to the registers. By 115 taking the cold air in at the top of the jacket A⁵ it will be readily understood that the air will be cleaner than if taken in at the base of the furnace, as has been heretofore the practice, since all furnaces at their base are 120 clogged with dust and ashes, the lighter particles of which will flow in with the inrushing air. The cap G being situated directly above the combustion-chamber is highly heated by those products of combustion which are conducted through the flues b, and hence the air after it is delivered from the air-boxes a⁵ to the spaces h² of the cap G is still further heated by said cap G before it escapes from 125 the drum A³.

130 By resting the flattened ends a³ of the castings a in the groove a⁴ of the bed-plate A' a tight joint is formed without the use, as heretofore, of cement, since a deposit of grit and

soot from the products of combustion as they pass through the space below the ash-pit will enter the groove and serve to seal the joint therein.

5 Having thus described the nature and objects of my invention, what I claim as new, and desire to secure by Letters Patent, is—

1. In a hot-air furnace, in combination with a fire-pot and a combustion-chamber, a series 10 of castings arranged around the fire-pot and combustion-chamber, said castings being provided with flanges adapted to overlap to form alternate flues and air-boxes, the lower end of said castings tapering to a substantially 15 flat portion to form below the fire-pot a circular wall, and a bed-plate arranged below the fire-pot and provided with an annular groove adapted to receive and support the flat portions of the castings, substantially as 20 and for the purposes described.

2. In a hot-air furnace, in combination with a fire-pot and a combustion-chamber, a series 25 of castings arranged around said fire-pot and combustion-chamber, said castings being provided with flanges adapted to overlap to form alternate flues and air-boxes, and a cap located 30 above the combustion-chamber and upon the castings, said cap having its interior in communication with the combustion-chamber and the flues and its exterior in communication with the air-boxes, substantially as and for the purposes described.

3. In a hot-air furnace, in combination with the fire-pot, combustion-chamber and exterior casing, of a series of castings arranged 35 adjacent to the fire-pot and combustion-chamber and within the casing, said castings being provided with flanges adapted to overlap to form alternate flues and air-boxes, a 40 cap located above the combustion-chamber and having its interior in communication with said chamber and with said flues and having its exterior in communication with the air-boxes, and an air-drum supported by said 45 casing and inclosing said cap, substantially as and for the purposes described.

4. In a hot-air furnace provided with an ash-pit, a fire-pot and a combustion-chamber, an offtake-pipe, branch pipes leading to the combustion-chamber and to the exterior of 50 the ash-pit, flues connecting the combustion-chamber with the exterior of the ash-pit, grooves or air-spaces formed in the wall of the fire-pot and communicating with the combustion-chamber, and with the interior of the 55 ash-pit, substantially as and for the purposes described.

5. A hot-air furnace, comprising an exterior casing, a hollow bed-plate supporting the casing, an air-drum supported upon the casing, an ash-pit supported within the casing above the bed-plate, a fire-pot and combustion-chamber arranged within the casing and above the ash-pit, a series of castings supported by the bed-plate and surrounding the 60 ash-pit, fire-pot and combustion-chamber, said castings having flanges adapted to overlap to form alternate flues and air-boxes, a cap 65 surmounting the combustion-chamber and supported by the castings, the interior 70 of said cap communicating with the combustion-chamber and the flues and the exterior of the cap communicating with the drum and the air-boxes, said flues opening into the space below the ash-pit and the air-boxes communicating with the interior of the hollow bed-plate, an offtake-pipe, branch pipes leading to the combustion-chamber and to the space below the ash-pit, and a jacket surrounding the offtake-pipe and open at its upper end for the reception of the cold air and communicating directly with the interior of the bed-plate, substantially as and for the purposes described.

In testimony whereof I have hereunto set my signature in the presence of two subscribing witnesses.

JOHN EVANS.
